10 Claims. (Cl. 19—70)

1
This invention relates to textile machinery and processes and in particular to roving machines and processes.

One object of this invention is to provide a process and apparatus for drafting or stretching a textile strand with a tension which is controlled automatically by the number of fibers in the cross section of the strand at a particular location.

Another object is to provide a process and apparatus for stretching a strand of roving wherein the electrical resistance set up in a selected portion of the strand automatically controls the amount of tension imparted to the strand, the strand having been previously rendered temporarily current-conducting, for example, by having been immersed in an electrolyte, or by having been treated with a colloidal solution of graphite or metal or with other finely divided conducting material.

Another object is to provide a process and apparatus, as set forth in the preceding objects, wherein the strand of roving is stretched between two spaced sets of toothed feeding and stretching rollers driven by separate electric motors, the forward motor being automatically controlled to rotate at a slightly higher speed than the rearward motor so as to impart a tension stretching to the strand.

Another object is to provide a process and apparatus, as set forth in the preceding objects, wherein the speed of the forward motor is regulated by an electrical control device in accordance with the electrical resistance of a portion of the strand passing between spaced contacts whereby the strand is stretched or tensioned in accordance with the thickness of the portion passing between the contacts.

Other objects and advantages of the invention will become apparent during the course of the following description of the accompanying drawings, wherein the figure shows diagrammatically one form of electrically controlled apparatus for automatically stretching or tensioning a strand of roving in accordance with its thickness, according to the present invention.

In the spinning of yarn, it is customary to draw out and slightly twist the strands of wool or cotton, this operation and the strand produced by it being termed "roving." In prior processes and apparatus for roving, the stretching or tensioning of the roving, known in the textile art as drafting has been controlled in accordance with the strength of the strand, regardless of its thickness. This has resulted in the strand being given a greater tension in its stronger portions than in

its weaker portions, and without relationship to its thickness. Hitherto, therefore, a strand of given strength has been stretched with the same tension regardless of whether the thickness of the strand is large or small.

2
In the process and apparatus of the present invention, the strand of roving is stretched or tensioned in accordance with the number of fibers which are present in a given portion of the strand 10 regardless of the strength of the strand as a whole, or of the distribution of the fibers. In the present invention, the strand is rendered current-conducting by being immersed in an electrolyte or by being treated with a colloidal solution 15 of graphite or metal or with other finely divided conducting material. An electric current is then passed through a portion of the strand which is being conducted through spaced stretching or tensioning rollers which are electro-mechanically 20 operated, the stretching or tensioning being controlled by the electrical resistance encountered by the current. Thus, the amount of current which passes through the selected portion of the strand depends directly upon the number of 25 fibers in the strand. If the number of fibers is large, so that the strand is strong, a stronger current passes through them and the strand is therefore stretched or tensioned more powerfully than when the number of fibers is small so that 30 the strand is weak, the electrical resistance higher and the current weaker.

Referring to the drawing in detail, the figure shows a preferred form of apparatus for automatically stretching or tensioning a strand 10 of roving composed of individual fibers 11. The showing of the individual fibers 11, is of course fanciful and purely by way of illustration since in practice the fibers would be in discontinuous lengths and far more closely packed so as to be 35 individually indistinguishable on the scale shown in the drawing. The strand 10 is first made temporarily electrically conducting by being immersed in a tank 12 containing an electrolyte 13 or a colloidal solution of graphite or metal 40 or having other means for applying fine particles of conducting material to the fibers 11. The finely divided conducting material may be applied to the fibers while in solution, the fibers then being dried. The finely divided conducting material may also be applied to the fibers in dry form. Since the current conductivity depends 45 upon the condition of dampness of the fibers, it is desirable to operate the machinery and carry 50 out the process in a room which is kept at a

constant humidity in order to obtain a constant strength of strand.

In order to eliminate short fibers or fibers lying crosswise in the strand, it is preferable to comb the strand prior to carrying out the process of the present invention. In this way, strands of maximum uniformity are obtained, the strand can be well spread out in breadth and the stretching process can be very sensitively controlled. Furthermore, in order to minimize the breaking of the fibers in the strand, it is advisable to separate the forward and rearward rollers 25-26 and 14-15 by a distance greater than the lengths of the fibers. The invention results in the obtaining of a product which is very uniform and which is adapted to be readily usable for fine spinning. The time-consuming doubling and trimming and repeated stretching of prior processes and apparatus is found to be unnecessary in practising the present invention.

The strand 10 after emerging from the tank 12 passes between grooved or roughened rearward feeding rollers 14 and 15 mounted on shafts 16 and 17. The shaft 16 carries a pulley 18 driven by a belt 19 from a pulley 20 on the output shaft 21 of an electric motor 22. The latter is provided with electric current from the power lines 23 and 24. The shaft 17 carrying the feed roller 15 may rotate freely but is preferably driven in synchronism with the shaft 16 but in the opposite direction so that the strand 10 is fed smoothly and evenly out of the tank 12. The shaft 17, for example, may be driven by gearing (not shown) from the shaft 16. In lieu of the belt 19 and pulleys 18 and 20, a sprocket chain and sprockets may obviously be substituted.

The forward end of the strand 10 passes between forward feeding rollers 25 and 26 mounted on shafts 27 and 28 respectively. The shaft 27 is driven in a similar manner to the shaft 16 in any suitable way, such as by a pulley 29 and a belt 30 from a pulley 31 on the output shaft 32 of an electric motor 33. The feeding roller 26 and shaft 28, as in the case of the feeding roller 15 and shaft 17, may rotate freely or may be positively driven in synchronism with the roller 25 and shaft 27, but in the opposite direction. As stated above, this may be accomplished by suitable gearing (not shown) arranged between the shafts 27 and 28.

In order to provide for a stretching or tensioning of the strand 10, the forward feeding rollers 25 and 26 are driven at a slightly higher speed by the motor 33 than the rearward feeding rollers 14 and 15 by the motor 22. According to the present invention, the speed of the motor 33 is regulated according to the number of fibers 11 momentarily present in a given location, such as the location between a pair of contact rollers 34 and 35 located on opposite sides of the strand 10 between the forward feeding rollers 25 and 26 and the rearward feeding rollers 14 and 15. The contact rollers 34 and 35 are mounted on shafts 36 and 37 respectively.

The upper contact roller 34 is engaged by a contact arm 38 which is connected as at 39 to a weight 40 or an equivalent spring (not shown) whereby the arm 38 is held in good electrical contact with the contact roller 34 and the latter in turn is urged downward to compress the fibers 11 forming the strand 10. Connected to the weight 40, as by the conductor 41 is a resistance-responsive motor controller 42 of a conventional type with the details of which the present invention is not concerned. The motor controller

42 is in turn connected by a conductor 43 to a contact arm 44 engaging the shaft 27 so that when the motor controller 42 is energized, a current may flow through a circuit indicated by the arrows, a part of which circuit is formed by the portion of the strand 10 which, at the moment, lies between the contact rollers 34 and 35 and the forward feeding rollers 25 and 26. In order to accomplish this, as previously stated, the strand 10 has been rendered temporarily electrically conducting by the liquid 13 in the tank 12.

The motor controller 42 is connected to the motor 33 which it controls by the conductors 45 and 46, and is energized from the power lines 47 and 48. The current supplied to the motor 33 through the conductors 45 and 46 from the power lines 47 and 48 is regulated by the motor controller 42 in proportion to the control current flowing through the circuit including the conductor 41, weight 40, contact arm 38, contact roller 34, strand 10, feeding roller 25, shaft 27, contact arm 44 and conductors 43. This control current, in turn, depends on the electrical resistance of the portion 49 of the strand 10 lying between the contact rollers 34 and 35 and the feeding rollers 25 and 26. The electrical resistance of the strand portion 49 moreover is dependent upon the number of fibers of which it is momentarily composed, the resistance of course being higher with a small number of fibers and lower with a large number of fibers.

In the operation of the invention, the strand 10 of roving is first immersed in the electrolyte 13 or other conduction-producing liquid and is then threaded between the rearward feeding rollers 14 and 15, the contact rollers 34 and 35 and the forward feeding rollers 25 and 26. The motors 22 and 33 are then started in operation by energizing the power lines 23, 24, 47 and 48. The motor 22 and accordingly the feeding rollers 14 and 15 are caused to rotate at a substantially constant speed, causing the strand 10 to be fed forward at a substantially constant speed.

The motor 33, however, is caused to rotate at a much higher speed than the motor 22, so that the forward feeding rollers 25 and 26, by rotating much more rapidly than the rearward feeding rollers 14 and 15, impart a stretching or tensioning to the strand 10. The motor 33 is caused to rotate at a variable speed under the control of the motor controller 42, in accordance with the resistance encountered by the control current passing through the above-described control circuit, including the strand portion 49. As the number of fibers in the strand portion 49 momentarily decreases, its electrical resistance rises, hence the control current in the control circuit falls. This causes the motor control 42 to reduce the current flowing through the conductors 45 and 46 to the motor 33, reducing the speed of the motor 33. When the number of fibers in the strand portion 49 momentarily increases, however, the resistance of the strand portion 49 decreases, whereupon the current flowing in the control circuit increases, causing the motor controller 42 to supply a greater amount of current to the conductors 45 and 46 so as to cause the speed of the motor 33 to increase.

Thus, according to the invention, the strand 10 is given a greater stretching or tension when the number of fibers in the strand portion 49 momentarily increases and the strand 10 therefore increases in tensile strength. Conversely, when the number of fibers in the strand portion

49 momentarily decreases, the stretching or tensioning of the strand 10 is automatically relaxed or decreased. In this manner, the rise and fall of the speed of the motor 33, as controlled by the motor controller 42 in accordance with the rise and fall of the resistance in the control circuit and particularly in the strand portion 49, automatically varies the tension or stretching of the strand 10 in accordance with the number of fibers in the strand portion 49 and therefore in 10 accordance with the tensile strength. If the number of fibers in the strand portion 49 is large, that is, if the strand is strong, then the strength of the current will be great and the strand will thus be stretched or tensioned more strongly 15 than if the number of fibers therein is relatively small.

What I claim is:

1. A process for automatically stretching a textile strand while preparing it for spinning, comprising rendering the strand electrically-conducting, electro-mechanically feeding the electrically-conducting strand at spaced forward and rearward locations along the strand, feeding the strand at said forward location at a higher speed than at said rearward location to stretch the strand at a predetermined tension while feeding it, passing an electric current through a portion of the strand being stretched, and varying the tension applied to said strand above and below 30 said predetermined tension in accordance with the variation in the electrical resistance of the current-carrying portion of the strand.

2. A process for automatically stretching a textile strand while preparing it for spinning, comprising rendering the strand electrically-conducting, electro-mechanically feeding the electrically-conducting strand at spaced forward and rearward locations along the strand, feeding the strand at said forward location at a higher speed than at said rearward location to stretch the strand at a predetermined tension while feeding it, passing an electric current through a portion of the strand being stretched, and varying the tension applied to said strand above and below 35 said predetermined tension in accordance with the increase and decrease of the electric current as governed by the variation in the electrical resistance of the current-carrying portion of the strand.

3. A process for automatically stretching a textile strand while preparing it for spinning, comprising rendering the strand electrically-conducting by applying a current-conducting substance to the strand, electro-mechanically feeding the electrically-conducting strand at spaced forward and rearward locations along the strand, feeding the strand at said forward location at a higher speed than at said rearward location to stretch the strand at a predetermined tension while feeding it, passing an electric current through a portion of the strand being stretched, and varying the tension applied to said strand above and below 40 said predetermined tension in accordance with the variation in the electrical resistance of the current-carrying portion of the strand.

4. A process for automatically stretching a textile strand while preparing it for spinning, comprising rendering the strand electrically-conducting by immersing the strand in a current-conducting liquid, electro-mechanically feeding the electrically-conducting strand at spaced forward and rearward locations along the strand, feeding the strand at said forward location at a 45

higher speed than at said rearward location to stretch the strand at a predetermined tension while feeding it, passing an electric current through a portion of the strand being stretched, and varying the tension applied to said strand above and below 50 said predetermined tension in accordance with the variation in the electrical resistance of the current-carrying portion of the strand.

5. Apparatus for automatically stretching an electrically-conducting textile strand while preparing it for spinning and adapted to be energized from a source of electric current, comprising a pair of spaced rotary feeding elements mounted in forward and rearward positions along the strand relatively to the direction of travel of the strand for feeding and stretching the strand, an electrical driving device drivingly connected to said forward feeding element, an electrical driving device drivingly connected to said rearward feeding element, spaced electrical contact members engaging spaced portions on a predetermined length of said strand, an electric circuit connecting said contact members with said source of electric current for passing said current through said predetermined length of strand, and an electrical control apparatus connected to said circuit and to the forward element driving device and responsive to the variation of the electric current passing through said length of strand for varying the speed of the forward element driving device within a speed range different from and higher than the speed of the rearward element driving device.

6. Apparatus for automatically stretching an electrically-conducting textile strand while preparing it for spinning and adapted to be energized from a source of electric current, comprising a pair of spaced rotary feeding elements mounted in forward and rearward positions along the strand relatively to the direction of travel of the strand for feeding and stretching the strand, a variable-speed electrical driving device connected to the forward feeding element, a substantially-constant-speed electrical driving device connected to the rearward feeding element, spaced electrical contact members engaging spaced portions on a predetermined length of said strand, an electric circuit connecting said contact members with said source of electric current for passing said current through said predetermined length of strand, and an electrical control apparatus connected to said circuit and to the forward element driving device and responsive to the variation of the electric current passing through said length of strand for varying the speed of the forward element driving device within a speed range different from and higher than the speed of the rearward driving device.

7. Apparatus for automatically stretching a textile strand while preparing it for spinning and adapted to be energized from a source of electric current, comprising an electrically-conducting substance applicator engaging said strand for rendering said strand electrically current-conducting, a pair of spaced rotary feeding elements mounted in forward and rearward positions along the strand relatively to the direction of travel of the strand for feeding and stretching the strand, an electrical driving device drivingly connected to said forward feeding element, an electrical driving device drivingly connected to said rearward feeding element, spaced electrical contact members engaging spaced portions on a predetermined length of said strand, an electric

circuit connecting said contact members with said source of electric current for passing said current through said predetermined length of strand, and an electrical control apparatus connected to said circuit and to the forward element driving device and responsive to the variation of the electric current passing through said length of strand for varying the speed of the forward element driving device within a speed range different from and higher than the speed of the rearward element driving device.

8. Apparatus for automatically stretching a textile strand while preparing it for spinning and adapted to be energized from a source of electric current, comprising an immersion appliance for immersing the strand in an electrical-conducting fluid, a pair of spaced rotary feeding elements mounted in forward and rearward positions along the strand relatively to the direction of travel of the strand for feeding and stretching the strand, an electrical driving device drivingly connected to said forward feeding element, an electrical driving device drivingly connected to said rearward feeding element, spaced electrical contact members engaging spaced portions on a predetermined length of said strand, an electric circuit connecting said contact members with said source of electric current for passing said current through said predetermined length of strand, and an electric control apparatus connected to said circuit and to the forward element driving device and responsive to the variation of the electric current passing through said length of strand for varying the speed of the forward element driving device within a speed range different from and higher than the speed of the rearward element driving device.

9. A process for treating an electrically conductive textile strand comprising stretching the strand under tension while feeding the same, passing an electric current through a portion of the strand being stretched, and varying the tension applied to the strand in accordance with variations in the electrical current flowing through the current carrying portion of the strand.

10. Apparatus for automatically stretching an electrically-conducting textile strand while preparing it for spinning and adapted to be energized from a source of electric current, comprising a pair of spaced rotary feeding elements mounted in forward and rearward positions along the strand relatively to the direction of travel of the strand for feeding and stretching the strand, a driving device drivingly connected to said forward feeding element, a driving device drivingly connected to said rearward feeding element, spaced electrical contact members engaging spaced portions on a predetermined length of said strand, an electric circuit connecting said contact members with said source of electric current for passing said current through said predetermined length of strand, and an electrical control apparatus connected to said circuit and to one of said driving devices and responsive to the variation of the electric current passing through said length of strand for varying the speed of said one driving device within a speed range different from and higher than the speed of the other driving device.
